UNITED STATES PATENT OFFICE.

FREDERICK WM. DUSTAN, OF CLARKSTON, WASHINGTON.

LOOSE-LEAF BINDER.

1,249,929.

Specification of Letters Patent. Patented Dec. 11, 1917.

Application filed September 25, 1916. Serial No. 122,038.

To all whom it may concern:

Be it known that I, FREDERICK W. DUSTAN, a citizen of the United States, residing at Clarkston, in the county of Asotin and State of Washington, have invented certain new and useful Improvements in Loose-Leaf Binders; and I do hereby declare the following to be a full, clear, and exact description of the invention, such as will enable others skilled in the art to which it appertains to make and use the same.

This invention relates to paper files and binders, and more especially to pins which are extensible and hinged; and the object of the same is to produce a binder for the insertion of loose leaves onto pins which are extensible as the thickness of the device increases, the binder having an intermediate plate serving as a guide for all the pins and two side plates each serving as a carrier for one set of pins and a lock for the other set, and all plates being hinged to the back plate and the hinging of the side plates thereto being such that it is effective only when they are unlocked from the pins. In carrying out this general idea the invention embraces many details of structure which will be more fully set forth in the following specification and claims, reference being had to the drawings wherein:

Figure 1 is a perspective view of this device with its side plates or locks open and one of them distended, portions of its intermediate plate being broken away to show the loose washers for the pins; Fig. 2 is an end view thereof, and Figs. 3 and 4 are sections on the lines 3-3 and 4-4 thereof respectively.

Fig. 5 is a perspective view of the device closed, parts being broken away to show the structure of the hinge for one side plate; Fig. 6 is an end view, and Figs. 7 and 8 are sections on the lines 7-7 and 8-8 of Fig. 5.

Fig. 9 is a plan view of the device closed, its side plates being turned outward and its intermediate plate turned to one side; and Fig. 10 gives details of the cutting of the inner edges of the leaves in two groups.

Fig. 11 is a detail of one of the pins with its parts separated,

Fig. 12 is a detail of one of the hinges for the side plates, and the parts which it connects.

Fig. 13 is a detail of the intermediate plate.

The back of the book or binding is indicated by the letter B in Fig. 1, and the covers by the letter C. The insertible leaves are in two groups lettered L and R in Fig. 10, and their inner edges are cut in a manner yet to be described. Otherwise this specification is not concerned with the elements which have been mentioned, and they are purposely omitted from the drawings for sake of clearness. The remaining parts which are preferably of metal constitute the loose leaf binder forming the subject-matter of the present invention.

To the binding B is secured in any suitable manner a back plate 1 of appropriate length and width, and hinged at 2 at the transverse center of this plate is an intermediate plate 3 normally upstanding at right angles to the back plate than which it is somewhat shorter. This intermediate plate is preferably of double thickness, as best seen in Fig. 13, its leaves being both provided near each end with upright slots 4 which register with each other when the leaves are connected face to face as by tangs 5 on one leaf passing through slits 6 in the other and turned down in a manner well understood, and possibly also by having the corners of one leaf turned over to embrace the corners of the other as at 7. The lower edges of the leaves may well respectively carry knuckles 8 and 9 engaging the pintles of the hinges 2. Between these leaves at each end of the plate are disposed loose washers 10 for a purpose yet to appear.

Along both edges of the back plate stand side plates which are duplicates of each other, and a description of one will suffice. It is made up of a lower bar 11 preferably notched at two points in its upper edge as 12, an upper bar 13, a pair of links 14 pivotally connecting these bars near their ends so that the bars must always stand in parallelism, and a lever 15 preferably of sheet metal with its body or handle bent into inverted U-shape and having a thumb piece 16, its lower end forked and passing astride both bars with its fork arms pivoted at 17 to the lower bar 11 and connected above the latter by a rivet 18 standing between the bars. Thus when the handle is raised the

lever turns around on its pivot 17 and the pin or rivet 18 raises the upper bar 13 out of contact with the upper edge of the lower bar, and therefore whatever may have been 5 clamped in the notches 12 is released.

The hinge 20 for each side plate is best seen in Fig. 12. It comprises an L-shaped member of stiff wire whereof one arm 21 extends always across the back plate 1 and 10 is rotatably mounted in a long tubular knuckle 22 fast thereon, the extremity of the arm being turned down as at 23 so that it cannot rotate while it stands within the knuckle, which it does when its side plate is 15 drawn outward. The other arm 24 is rotatably mounted in a long tubular knuckle 25 attached to or formed as a part of the inner fork arm of the lever 15 and standing parallel with the length of its handle. 20 It follows that when this lever is turned down to close the bars of the side plate, the knuckle 25 stands in a horizontal plane and the entire side plate may be rocked outward on the arm 24 as a hinge. The cross arm 21 25 rocks in the knuckle 22 as a hinge when the lever is thrown upward, but in that position the side plate cannot be turned outward because the arm 24 is no longer horizontal.

Directly engaging the leaves are devices 30 commonly known as "pins" but which in my invention are of peculiar construction as best seen in Fig. 11. Each is in two pieces or members telescopically mounted on each other, the inner member being tubular and 35 the outer member preferably flattened and flexible. Said inner member 31 has an eye or knuckle 32 at its inner end engaging a staple 33 carried by the lower bar 11 of the side plate to which it is hinged, and from 40 this eye the member rises in an elbow 34 and then projects inward over the back plate 1 and is tubular as seen at 35. The other or outer member 36 is preferably a strip of 45 flexible metal whose inner end passes into the tubular portion 35 of the inner member and is turned down or headed at its extremity as at 37, whose body passes loosely through a slit 38 in one of the loose washers 10, and whose outer end is enlarged or 50 headed as at 39. In the drawings I have shown two of these pins connected to the left hand side plate near its ends and passing through the outermost slots 4 in the intermediate plate and through the loose washers 55 between the leaves of the same, and two other similar pins connected with the right hand side plate and passing through the remaining slots in the intermediate plate. When the device is collapsed as seen in Fig. 60 5, the outer members 36 of all the pins are telescoped into the inner members 31 and yet project sufficiently therefrom so that each passes completely across the back plate and between the bars 11 and 13 of the opposite side plate, engaging a notch 12 therein and

being held in such notch by the closing down of the upper bar 13. When the device is open as seen in Figs. 1 to 4, these pins are distended, and the outer member of each slides outward in the tubular portion 35 of 70 its inner member—perhaps as far as the downturned inner extremity thereof will permit, while the head 39 comes up against the loose washer 10 to prevent the entire separation of parts. At this time the downturned extremity 23 of each cross arm 21 has been slid outward within its knuckle 22 within which it cannot now rotate, and therefore the side plate which is distended is locked with its bars open and its lever upright. 75

The use of this device will be best understood by reference to Figs. 1 and 10. Assuming that each side plate carries only two pins and that they are disposed as shown and described, the inner edges of the left leaves will be provided with two holes at H' and two notches at N', and the inner edges of the right leaves R will also have holes H and notches N but their disposition will be 80 the reverse of those on the left leaves. The intermediate plate 3 divides the binder into halves, and the leaves when inserted in these halves form a group at the right side and a group at the left side of said plate. To 85 insert a leaf into the left hand group for instance, the left lever 15 is raised by means of its thumb piece 16, its upper bar 13 is thereby lifted off its lower bar 11 so that the heads 39 of the pins on the right side 90 plate are released and the outer members 36 of these pins may be telescoped into their inner members 31, whereas the pins of the left side plate are fully distended when such plate is drawn away from the back 95 plate, and yet their heads 39 and extremities 37 prevent the entire disconnection of parts. A left hand leaf L may now be inserted by 100 passing its notches N astride the left hand pins until its holes H come opposite the heads of the right hand pins which latter have been telescoped and are therefore shorter. Then the left side plate is pushed inward, and the heads of the right pins 105 passed between its bars, and when the lever 110 15 is borne downward these bars come together to lock the pins as has been explained. The same operation will be followed to insert a right hand leaf R excepting that it would be at the other side of the intermediate plate 3. While either or both side plates are distended and open, they must 115 remain upright because the arms 24 of their hinges are upright, but when they are closed as seen in Fig. 1 their hinges 20 permit the 120 side plate to be turned down so as to allow the leaves of the book to lie open, and the hinge connection 32—33 between each pin 125 and its side plate assists. Also the hinging of the intermediate plate to the back plate 130

permits the leaves of the book to be thrown over from one side to the other, and therefore the operator is not confined to opening the book always at its center and throwing the right hand group of leaves to the right and the leaves in the other group to the left.

Especial attention is called to the use of the downturned extremities 23 of the hinges 10 20. I prefer to employ these extremities, but they might be omitted. Each is preferably turned from the cross arm 21 in a direction opposite to that in which the arm 24 projects therefrom. It follows that when the 15 lever is thrown upward and the arm 24 is raised, the extremity 23 is turned downward and in that position it may slide through the knuckle 22. The entire separation of the 20 side plate from the remainder of the device is now prevented by the heads 39 of the pins, and the inner arm 21 is of such length that it does not draw out of the knuckle 22 when the pins are fully distended and their heads 25 39 come up against the washers 10. When the side plate is again closed to a position about over the edge of the back plate, the extremity 23 is projected completely through the knuckle 22, and thereafter when the lever is closed the cross arm 21 turns in said 30 knuckle and its extremity is turned aside so that it may no longer be drawn through the knuckle. Therefore the use of this extremity locks the side plate against its being withdrawn from a position about coincident 35 with the side edge of the back plate excepting only when its lever is raised. With this detail omitted there would be no such lock, and the result would be that a larger number of leaves could be inserted in either 40 group, although the device as a whole would be looser in its binding because its side plates could move out and in freely.

Especial attention is called to the use of the loose washers 10, the flexibility of the 45 pins, and the hinging of the intermediate plate 3. It may often occur with the use of this device that practically two complete books may be held in one binding—one within the right group and the other within the 50 left group of leaves—and if so, one group may build up faster than the other or even quite in advance altogether thereof. The result would be that there would be substantially no leaves at one side of the intermediate plate, and frequent call to turn over the many at the other side thereof—hence the advantage of the hinges 2. Also the fact that the washers may slip up and down between the leaves of the intermediate plate 55 60 is of advantage, especially where leaves are inserted at one side of such plate and none at the other. Finally, the flexibility of the outer members 36 of the pins not only permits such movement of the washers as the 65 insertion and removal and use of the leaves

renders desirable, but permits the turning outward of the side plates—especially if the notches 12 are so shallow as to quite closely engage the free ends of the pins.

What I claim is:

1. In a loose leaf binder, the combination with a back plate, a pair of side plates, a series of extensible pins hingedly connected with each side plate, and means on each side plate for detachably engaging the heads of the pins on the other side plate; of means whereby each side plate is hingedly connected with the back plate and capable of lateral movement relative thereto.

2. In a loose leaf binder, the combination with a back plate, a pair of side plates, a series of extensible pins hingedly connected with each side plate, and means on each side plate for detachably engaging the heads of the pins on the other side plate; of a hinge 80 connecting each side plate with the back plate and comprising an L-shaped member, a transverse knuckle on the back plate, and a longitudinal knuckle on the side plate loosely receiving the arms of said member. 85

3. In a loose leaf binder, the combination with a back plate, a pair of side plates each composed of two bars and a lever for moving them into contact edge to edge, and a series of pins hingedly connected with the 90 lower bar of each side plate and passing between the bars of the other side plate; of a hinge connecting each side plate with the back plate and comprising an L-shaped member, a transverse tubular knuckle on the back 95 plate in which one arm thereof is rotatably and slidably mounted, and a longitudinal tubular knuckle on the lever of each side plate in which the other arm of said member is rotatably mounted.

4. In a loose leaf binder, the combination with a back plate, and a pair of side plates whereof each comprises a lower bar notched in its upper edge, an upper bar overlying the same, links pivotally connecting said bars and holding them in parallelism, and a lever having its lower end forked and pivoted to the lower bar, its fork-arms connected by a rivet for raising the upper bar; of a series of telescopic pins each comprising an inner member hinged to the lower bar of one side plate and an outer member whose inner end telescopes in said inner member and whose outer end passes through a notch in the opposite side plate and is headed, 110 115 tubular knuckles secured across the back plate and along the inner fork-arms of the levers, and L-shaped hinge members each having its inner arm rotatably and slidably mounted in one knuckle of the back plate 120 and its outer arm rotatably mounted in the knuckle of one lever whereby the side plates may swing when the levers are depressed but are held upright when the levers are raised.

5. In a loose leaf binder, the combination with a back plate; and a pair of side plates whereof each comprises upper and lower bars, links pivotally connecting said bars and holding them in parallelism, and levers for moving them together and apart; of a series of pins each composed of an inner member hinged to the lower bar of one side plate and an outer flexible member whose 10 inner end telescopes within its inner member and whose outer end passes between the bars of the opposite side plate and is headed, a pair of tubular knuckles secured across the back plate, other tubular knuckles secured to the inner fork-arms of said levers, two L-shaped hinged members whereof the outer arm of each is rotatably mounted in the knuckle of one lever and the inner arm is rotatably and slidably mounted in one of 15 the knuckles of the back plate and has its inner extremity turned down, for the purpose set forth.
6. In a temporary binder, the combination with a back plate, a pair of side plates 20 hingedly and slidably mounted with relation to the edges of said back plate, and a series of extensible pins connected with each side plate and leading across the back plate to and through the opposite side plate; of an 25 intermediate plate hingedly mounted on the back plate and having slots through which said pins project.
7. In a temporary binder, the combination with a back plate, a pair of side plates hingedly and slidably mounted with relation to 30 the edges of said back plate, and a series of extensible pins connected with each side plate and leading across the back plate to and through the opposite side plate; of an 35 intermediate plate hingedly mounted on the back plate and having slots through which said pins project.
8. In a temporary binder, the combination with a back plate, a pair of side plates hingedly mounted with relation to the edges of 40 said back plate, and a series of pins connected with each side plate and leading across the back plate to and through the opposite side plate; of an 45 intermediate plate hingedly mounted on the back plate and having slots through which said pins extend.
9. A loose leaf binder comprising a back plate, two side plates and an intermediate plate hingedly connected with the back plate, a series of extensible pins hingedly connected with each side plate and leading through the intermediate plate and the other side plate, means for preventing the spreading of the plates when they are collapsed to 50 positions near the edges of the back plate, and manually operated means to release the spreading means.
10. A loose leaf binder comprising a back plate, two side plates and an intermediate plate hingedly connected with the back plate, a series of extensible pins hingedly connected with each side plate and leading through the intermediate plate and the other side plate, means in each side plate for engaging the ends of the pins of the other side plate, and means for preventing the spreading of the plates while the pins are so engaged but adapted to release the plates when 55 the pins are disengaged.
11. A loose leaf binder comprising a back plate, two side plates and an intermediate plate hingedly connected with the back plate, a series of extensible pins hingedly connected with each side plate and leading through the intermediate plate and the other side plate, means on each side plate for engaging the tips of the pins of the other side plate while permitting the side plate to rock, and means for disengaging said tips and locking the plate against said rocking movement.
12. A pin for temporary binders comprising an inner member having a support at its inner end and its outer end made tubular, and an outer member whose body is slidably mounted in the tubular portion of the inner member, the inner extremity of the outer member being turned down and the outer extremity being headed.

In testimony whereof I affix my signature in presence of two witnesses.
